MECHANICAL PENCIL

Lucifer J. Most, Hudson County, N. J.

Application March 30, 1940, Serial No. 326,859

4 Claims. (Cl. 120—18)

My invention relates to mechanical pencils and has reference particularly to the means for actuating the lead. The leads used in this type of mechanical pencil have a very limited cross-sectional area and their total mass or weight is rather slight. It, therefore, becomes necessary to provide means for insuring the engagement of the lead with the means for actuating it at the time the engagement is to take place between them, for gravity alone is not sufficient to insure such engagement. Other objects of the invention will be pointed out hereinafter, or will be apparent to one skilled in the art from the disclosure herein.

In the appended drawing forming part of this application, Figure 1 is an enlarged vertical section on line 1—1, Figure 2 through the lower end of a mechanical pencil embodying my invention; no leads are shown to better illustrate the invention.

Figure 2 is an enlarged cross-section on line 2—2, Figure 1.

Figure 3 is a similar section on line 3—3, Figure 1.

Figure 4 is an enlarged section on line 4—4, 25 Figure 2 of the tip end.

Figure 5 is an enlarged top end view of the interiorly threaded member showing its engagement with a lead.

Figure 6 is an enlarged section on line 6—6, 30 Figure 5, and

Figure 7 is a view similar to that of Figure 5, showing the interiorly threaded member provided for a lead of different cross-section than that shown in the other figures.

Referring to the figures, 10 is a barrel which terminates with a tip 11 coupled with the barrel to participate in all the movements thereof. The tip 11 is provided at its extremity with a bore 12 of a circular cross-section to frictionally engage a lead fed therethrough. As shown the tip end of the bore is split to obtain the frictional contact but any other suitable means for that purpose may be used. The bore 12 enters into an enlarged circular bore 13 in which is mounted revolvably a tube 14. The upper portion of said tube is revolvably mounted in a bushing 15 keyed to the barrel, as indicated at 16. The upper end of the tube 14 enters an enlarged recess 17 in the bushing and thereat carries an exterior gear 18 constrained to revolve with the tube. At the lower end the tube 14 carries within an interiorly threaded member 19, also constrained to revolve with the tube.

A pinion 20 revolvably mounted in the bushing 15 is in mesh with the exterior gear 18 and an interior gear 21 formed in a ring 22. The ring 22 is coupled to a magazine tube 23 to revolve therewith.

Mounted within the tube 14 is a tube 24 which 60

permits the tube 14 to revolve freely about it. The upper end of the tube 24 projects out of the tube 14 and thereat carries a washer 25 firmly secured to the exterior end of the tube 24, and 5 also firmly secured in the enlarged recess 17 of the bushing 15. The washer 25 also serves as means for preventing longitudinal displacement of the pinion 20 in the bushing. The lower end 26 of the tube 24 is swedged to form a lead guide 10 of the desired cross-sectional shape that will by its contour prevent a lead of cooperative cross-sectional contour from turning therein while permitting the lead to move longitudinally. In this particular case, the contour of the lead guide 26 15 is triangular and it is in alignment with the threaded member and the bore 12, which bore also forms a frictional lead guide below the threaded member. The diameter of the bore 12 is slightly less than the diameter of the circle inscribing the edges of the lead.

Positioned within the magazine tube 23 is a washer 27, which forms the bottom of said tube and with which it forms the magazine for leads. The washer is shaped to facilitate the movement of the leads from the magazine into the tube 24 from where it enters the swedged end 26 of said tube, which swedged end constitutes the lead guide leading to the threaded member 19. This washer 27 may be coupled to the magazine tube 23, or if desired, free thereof and coupled to the washer 25. In either arrangement it will perform the function described.

As will be seen from Figures 1 and 4, the interiorly threaded member with its tube 14 by 35 which it is driven are so proportioned that when the pencil is assembled, the lower end of the threaded member bears on the bottom of the bore 13 in the tip. The longitudinal movement of the threaded member and the tube is prevented by the washer 25 in the recess 17 and the contact of the lower end of the swedged end 26 with the upper face of the threaded member 19.

To insure a positive engagement of a lead 28 with the interiorly threaded member 19, I provide notches 29 in the upper end of the threaded member, that is, the face adjacent to the lead guide 26 which guides a lead from the magazine or tube 24 to the threaded member 19. These notches 29 are cut radially in the wall of the threaded member 19 and the number of those notches corresponds to the number of angles the lead has. In this particular case, the lead is shown triangular, and therefore three notches have been cut. The width of the notches are such that they would easily accommodate that portion of the lateral surface of the lead which is to be engaged by the threads of the member 19.

As the magazine tube 23 is revolved relatively to the barrel 10, the ring 22 is revolved therewith, causing the interior gear 19 to turn the

pinion 20, which in turn revolves the gear 18 and therewith the tube 14, which carries the interiorly threaded member 19. The bore 12 which forms the frictional lead guide in the tip and the swedged end 26 which also forms a lead guide above the threaded member, are stationary, being coupled to the barrel as previously described. In consequence of the rotation of the threaded member 19 relatively to the lead guides 12 and 26, the notches 29 of the threaded member will intermittently register with the adjacent angular portions or the lead guide above the threaded member, thereby permitting the angular portion 31 of a lead ready to engage the threaded member 19 to enter into the notches 29, through an axial depth of the said notches 29. This axial depth must be at least that of a complete convolution of a thread. In consequence of this engagement of the lead portions 31 with the cut away portions in the thread 30 a positive engagement takes place and the further rotation of the threaded member 19 causes the threads to cut into the portion of the lead which lies in the notches within the threaded part 30.

By this means I provide a positive engagement between the threaded member and the lead coming thereto and insure the progress of said lead from the lead guide 26 through the threaded member and thereafter through the lead guide 12.

Although the effective part of the notches 29 is within the threaded depth of the member 19, the reason for cutting those notches across the face of the threaded member is the fact that the wall thickness of the interiorly threaded member is very small and to make those notches only within the depth of the thread 30 of the threaded member is impractical.

The frictional lead guide formed by the bore 12 in the tip comes into play only when a lead fed by the threaded member leaves the lead guide 26. It is then that its frictional engagement with the lateral edges of the lead therein prevent its turning when the threaded member is turned, thereby enabling the feeding out of a lead portion from the threaded member. The piece of the lead that may be still engaged in the frictional lead guide 12 is forced out by a lead following it through the threaded member. The threaded portion of the lateral surface of the lead provides a better frictional engagement between the lead and the yielding bore forming the frictional lead guide 12 in the tip than a smooth lead surface.

In Figure 7, the threaded member 19' is shown with notches 29' to accommodate a lead of oval cross-section. It is evident that the lead guides will also be of oval cross-section, and the registration of said notches 29' with the longer axis of the oval will permit the lead to enter into the threaded member and provide means for a positive engagement between the lead and the threaded member.

It is self-evident that if the cross-section of the lead pencil is polygonal as distinguished from the triangular, the number of notches will correspond thereto. Furthermore, for an oval lead pencil, as shown in Figure 7, four notches may be provided, and for a triangular lead as shown in Figure 5, six notches may be provided, in which case the registration between the cooperating parts of the guide and threaded member will take place at shorter intervals.

I claim:

1. In a mechanical pencil, an interiorly threaded member for engaging a lead directly, a lead guide for directing a lead to the member and having means inherent to its shape for preventing a lead shaped to cooperate with the guide from turning in the guide but permitting the lead to move longitudinally, a second lead guide of circular cross-section for frictionally engaging a lead coming from the threaded member to prevent its turning in the second guide, and means for turning the threaded member relatively to the guides.
- 15 2. In a mechanical pencil, an interiorly threaded member for engaging a lead directly, a lead guide for directing a lead to the member and having means inherent to its shape for preventing a lead shaped to cooperate with the guide from turning in the guide but permitting the lead to move longitudinally, a second lead guide of circular cross-section for frictionally engaging a lead coming from the threaded member to prevent the lead from turning in the second guide, and means for turning the threaded member relatively to the guides, said threaded member having means in the end adjacent to the first guide for positively engaging the entering end of lead before said end of lead is engaged by the threads of the member.
- 20 3. In a mechanical pencil, an interiorly threaded member for engaging directly a predetermined portion of the lateral surface of a lead, a lead guide for directing a lead to the member and having means inherent to its shape for preventing a lead shaped to cooperate with the guide from turning in the guide but permitting the lead to move longitudinally, a second lead guide of circular cross-section for frictionally engaging the lead coming from the threaded member, said frictional engagement of the second guide with the lead prevents the lead from turning in the second guide, and means for turning the threaded member relatively to the guides, said threaded member having means for engaging the end portions of the lateral surface of the lead to be threaded before the threads of the member engage said surface.
- 25 4. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 30 5. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 35 6. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 40 7. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 45 8. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 50 9. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 55 10. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 60 11. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 65 12. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
- 70 13. In a mechanical pencil, a barrel having a tip provided with a lead outlet of circular cross-section shape to frictionally engage a lead therein to prevent the lead from turning in the outlet, a threaded member in the tip adjacent to the lead outlet, a tubular member housing the threaded member and coupled with it and rising above the same within the tip, a second tubular member within the first and revoluble relatively thereto, said second tubular member having a reduced portion in proximity of the threaded member shaped to form a lead guide having means inherent to its shape for preventing a lead shaped to cooperate with the guide from turning in said guide while permitting the lead to move longitudinally, a lead magazine in the barrel having means for directing leads into the second tubular member, and motion transmission means from the magazine to the first tubular member, said threaded member having means in proximity of the reduced portion of the second tubular member to permit a lead to enter thereto before the threads of said threaded member engage the lead therein.
